UNITED STATES PATENT OFFICE.

WILBER D. FORSYTH AND ENOS T. BELL, OF PITTSBURG, PENNSYLVANIA,
ASSIGNORS TO THE UNION BOILER TUBE CLEANER COMPANY, OF PITTSBURG, PENNSYLVANIA, A CORPORATION OF PENNSYLVANIA.

BOILER-TUBE CLEANER.

SPECIFICATION forming part of Letters Patent No. 698,193, dated April 22, 1902.

Application filed January 17, 1899. Serial No. 702,472. (No model.)

To all whom it may concern:

Be it known that we, WILBER D. FORSYTH and ENOS T. BELL, citizens of the United States, and residents of Pittsburg, in the county of Allegheny and State of Pennsylvania, have invented certain new and useful Improvements in Boiler-Tube Cleaners; and we do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a representation of a perspective view, partly broken away, showing the invention as in application. Fig. 2 is a side elevation, partly in section, of the motor-bracket and driving-gear. Fig. 3 is an 20 end elevation of same. Fig. 4 is a detail view illustrating the stud C³ of the bracket.

This invention has relation to devices for operating boiler-tube cleaners and is designed to provide means whereby the feed-rod of a 25 boiler-tube cleaner may be driven by a direct motor connection therewith while capable of being readily moved from one tube of a boiler to another.

With this object in view the invention consists in the novel construction and combination of parts, all as hereinafter described, and pointed out in the appended claims.

Referring to the accompanying drawings, the letter A designates the feed-rod of a boiler-tube cleaner, (indicated at B,) said rod in operation being rotated at a high rate of speed, while at the same time it is moved longitudinally to carry the cleaner through the tube being cleaned.

40 C designates a bracket or casting which is mounted to slide laterally upon a flanged guide rail or bar D, being actuated by a feed-screw D'. Said screw has a bearing at each end portion in lugs d of the bar or rail D and 45 engages a nut C' of the casting C. It is provided at each end with an operating-handle D². The slide portion C², which engages the bar or rail D, is made in two sections, which are bolted or clamped together and seat be-

tween them a depending cylindrical stud or 50 stem C³ of the bracket proper at the forward portion of the bracket. By loosening the bolts which clamp this stud or stem the motor and feed-rod may be readily turned thereon to enable the feed-rod to enter a tube of 55 the boiler which may have become warped at its extremity. The intermediate portion of the bracket or casting rests and turns upon the slide. The bar D is mounted to move vertically in guides e of triangular supporting- 60 brackets F, which are set up adjacent to the end of the boiler to be cleaned. For the purpose of moving the bar in these guides windlasses F and rope connections F' are shown. We do not, however, confine ourselves to any 65 particular means for supporting and moving the said bar or rail, as various devices may be employed for that purpose. The arrangement shown and described has, however, proved very satisfactory and convenient for 70 the purpose.

G designates a motor or engine, the base portion G' of whose casing is securely bolted or otherwise secured to the bracket or casting C. This motor or engine may be of any 75 suitable rotary type, operated by steam, water, electricity, or other suitable power. A steam-motor is, however, preferred, as it may be readily coupled up to the steam-generators of the plant in which the apparatus is being 80 used. The shaft G² of the motor is journaled at one end in bearings H, mounted in a vertical arm of the bracket or casting, and has fixed thereto a spur gear-wheel I. The bracket or casting also has a horizontal forwardly-extending arm C⁴, provided with a transversely-split boxing C⁵, in which is a compound sleeve J, turning in bearings J', and having fixed centrally thereto a spur-wheel K, whose teeth mesh with the teeth of the spur-wheel I. The 90 said wheel K works in the space separating the sections of said boxing, which are connected by a semicircular enlargement thereof. The inner section of the sleeve J has an internal keyway j, which is slidingly engaged 95 by a spline or rib a on the feed-rod A. The inner section of this sleeve J is removable endwise from its outer concentric section, to

which it is keyed at j' , and is prevented from such removal by the clamp J^2 .

L designates a casing which surrounds the gear-wheels I and K , being secured to the 5 boxing enlargement above referred to at the top and bottom thereof.

In operation the bracket or casting C is adjusted on the bar or rail D to bring the feed-rod into alignment with the particular tube 10 of the boiler which is to be cleaned, the said bar or rail D being also adjusted vertically to bring it into proper relation to the horizontal series of tubes in which such tube is situated. The cleaner is introduced into the 15 tube and the motor is started, thereby through the gears I and K rotating the feed-rod. As the operation continues the said rod is pushed longitudinally into the tube, its spline a sliding in the keyway of the sleeve J . A small 20 stream of water should be kept flowing into the tube during the operation to prevent heating and to remove the loosened and disintegrated scale. As soon as one tube is completely cleaned the bracket or casting C is 25 moved laterally on the bar or rail D into proper position for the next tube in the same horizontal row or series, and when that row or series is cleaned the bar or rail is raised or lowered on its guides to bring the devices 30 into proper position for the next row or series.

Having thus described our invention, what we claim as new, and desire to secure by Letters Patent, is—

1. In mechanism of the class described, the 35 combination of the transverse bar or rail, means for vertically adjusting the same, the laterally-adjustable slide carried by said bar or rail, the bracket having the cylindrical downward extension and the upward extension, the clamp upon said slide engaging said downward extension, the outer rotary sleeve journaled in said bracket, the inner concentric endwise-removable sleeve rotatably connected to said first-named sleeve, means for 40 securing said inner sleeve from endwise movements, the feed-rod engaging said inner sleeve, the rotary engine carried by said bracket, the shaft of said engine, having a journal-bearing in said upward extension, and carrying 45 a gear-wheel meshing with the gear-wheel upon said outer sleeve, substantially as specified.

2. In mechanism of the class described, the 50 combination of the transverse bar or rail, means for vertically adjusting the same, the

laterally-adjustable slide carried by said bar or rail, the bracket upon said slide, having a transversely split cylindrical boxing, and the semicircular enlargement connecting the sections of said boxing, the rotary sleeve journaled at opposite ends thereof in said boxing, the gear-wheel mounted centrally of said sleeve in the space separating the sections of said boxing and partly inclosed by said enlargement, the feed-rod engaging said inner 60 sleeve, the rotary engine carried by said bracket, the shaft of said engine carrying a gear-wheel meshing with said first-named gear-wheel, and the guard-strip secured at one end thereof to the upper portion of said 65 enlargement, carried around the gear-wheel upon the engine-shaft, thence partly around the gear-wheel upon said sleeve, and secured to the lower portion of said enlargement, substantially as specified. 70

3. In mechanism of the class described, a transverse bar or rail, a laterally-adjustable slide mounted upon said bar or rail, a bracket upon said slide, and having a cylindrical downward extension at one end portion thereof, 80 clamped to said slide and revoluble therein to allow said bracket to be turned, a rotary sleeve having bearings in the opposite end portion of said bracket, the intermediate portion of said bracket resting and turning upon the upper surface of said slide, a feed-rod actuated by said sleeve, and a rotary engine mounted upon said bracket, and geared to said sleeve, substantially as specified. 85

4. In mechanism of the class described, a 90 transverse bar or rail, a laterally-adjustable slide carried by said bar or rail, a bracket upon said slide having a boxing at one end portion thereof, an outer rotary sleeve journaled in said boxing, an inner endwise-removable sleeve rotatably engaged by said 95 first-named sleeve, a clamp upon said bracket and engaging the outer end of said inner sleeve, a feed-rod actuated by said inner sleeve, and a rotary engine carried by said 100 bracket, and geared to said outer sleeve, substantially as specified.

In testimony whereof we affix our signatures in presence of two witnesses.

WILBER D. FORSYTH,
ENOS T. BELL.
